(57) **CLAIM**

The ornamental design for a cooking pot handle, as shown and described.

DESCRIPTION

FIG. 1 is a top, rear and right side isometric view of a cooking pot handle showing my new design, the cooking pot shown in broken lines;

FIG. 2 is a bottom, rear and left side isometric view thereof;

FIG. 3 is a top plan view thereof;

FIG. 4 is a bottom plan view thereof;

FIG. 5 is a front elevation view, the rear elevation view being obscured by the cooking pot;

FIG. 6 is a right side elevation view, the left side elevation view being a mirror image thereof;

FIG. 7 is a cross-sectional view taken along line 7-7 of FIG. 3;

FIG. 8 is a top, rear and right side isometric view of a cooking pot handle shown removed from the cooking pot;

FIG. 9 is a bottom, front and right side isometric view thereof;

FIG. 10 is a top plan view thereof;

FIG. 11 is a bottom plan view thereof;

FIG. 12 is a rear elevation view thereof;

FIG. 13 is a front elevation view thereof;

FIG. 14 is a right side elevation view, the left side being a mirror image thereof; and,

FIG. 15 is a cross-sectional view taken along line 15-15 of FIG. 10.

The broken lines shown in the drawings are included for the purpose of illustrating environmental structure and form no part of the claimed design.
